UNITED STATES PATENT OFFICE.

HENRY IVERSEN, OF CORSICANA, TEXAS.

ELECTRIC CLOCK.

No. 839,765.

Specification of Letters Patent.

Patented Dec. 25, 1906.

Application filed September 16, 1905. Serial No 278,741.

To all whom it may concern:

Be it known that I, HENRY IVERSEN, a citizen of the United States, residing at Corsicana, in the county of Navarro and State 5 of Texas, have invented new and useful Improvements in Clocks, of which the following is a specification.

This invention relates to a novel clock system in which a secondary clock or a series of 10 secondary clocks are electrically operated from a master-clock.

The invention has to do more particularly with the construction of the secondary clock and with the circuit-breaker operated from 15 the master-clock.

It is the object of the invention to provide a system whereby a series of clocks may be located at any number of different localities in a city or in different rooms of a building and 20 be operated from a master-clock, so that all the secondary clocks will be caused to keep uniform time with the master-clock. By such a system it is only necessary to regulate the master-clock to insure that all of the secondary cocks keep uniform time therewith.

In order that the invention may be clearly understood, I have illustrated the same in the accompanying drawings, in which—

Figure 1 is a front view, partly in section 30 and partly in elevation, of a secondary clock. Fig. 2 is a front view of the master-clock. Fig. 3 is a side elevation of the secondary clock. Fig. 4 is a detail view illustrating one 35 position of the operating and locking-arms, the locking-arm being in an inoperative position. Fig. 5 is a similar view with the operating-arm in an inoperative position. Fig. 6 is a detail view of one member of a circuit-breaker, and Fig. 7 is a diagrammatic perspective view showing the circuit-breaker of 40 the master-clock electrically connected with the electromagnets of a secondary clock, together with the mechanism operated by said electromagnets, and a circuit make and 45 break device for setting the hands of the secondary clock independently of the movement of the master-clock.

Referring now to the drawings, 1 indicates the master-clock, which comprises the ordinary 50 clockwork mechanism with arbors 2 3 for the minute and hour hands, respectively. On the shaft 4 of the escapement-wheel 5 of this clock is secured to turn with said shaft a rotary make-and-break device 6, having an 55 outer circumferential layer 7 of hard rubber

or other insulating material, in which is embedded at three or more equidistant points around the circumference contact-pieces 8, of suitable metal, preferably platinum.

9 10 indicate two similar contact-arms 60 which are secured upon insulating-blocks 11 12, said insulating-blocks being independently and loosely mounted upon a journal 13, carried by a bracket-frame 14, secured to the frame 15 of the master-clock. The ends 65 of the contact-arms 9 10 rest upon a rotary contact-maker 6 and are adapted to make contact at their outer ends with the contact-pieces 8 as the rotary contact-maker is revolved by the clockwork mechanism of the 70 master-clock.

16 indicates a secondary clock, in the frame 17 of which the mechanism of said clock is mounted. Said mechanism includes two electromagnets 18 and 19, respectively. 75 From the rear end of the contact-arm 9 a wire 20 passes to the electromagnet 18. From the rear end of the contact-arm 10 a wire 21 passes to and is connected with one pole of an electric battery 22. A wire 23 80 connects the other pole of said battery with the electromagnet 19.

24 indicates an armature which is substantially segment-shaped, as shown, and is pivotally supported by bearings 25 at opposite 85 ends in sides of the frame 17. The cores 26 of the electromagnets are curved to conform to the curved side of the armature, and when said electromagnets are energized the armature will be caused to rotate on its bearings 90 25, or, in other words, sweep across the upper surfaces of the cores 26. The purpose of this construction will be presently explained.

Secured centrally to the upper side of the armature 24 and extending at right angles from opposite sides thereof is a lever-arm 27, loosely secured or swiveled, toward the outer end of which is a depending operating-arm 28. On the outer end of said lever-arm is mounted an adjustable weight 29. Secured toward the upper end of the operating-arm 28 is a bracket-arm 30, provided with an offset portion having an elongated slot 31, which works over the outer end of the lever-arm 27. The purpose of the bracket-arm 30 is to insure uniformity of movement to the operating-arm 28. In the lower end of the operating-arm 28 is secured a pin 32, having an upper inclined side, as indicated at 33 in Fig. 5. This pin is adapted to engage in any one of a circular 105 110

series of apertures 34, formed in a wheel 35, which is fixedly secured on a shaft 36, which latter is rotated from said wheel. A guide-arm 37 is pivotally mounted at one end on the shaft 36 and at its other end is pivotally secured to the butt-end of the pin 32, the purpose of this guide-arm being to insure the travel of the pin 32 in an arc concentric with the periphery of the wheel 35, so that the said pin 32 will always be in position at the proper time to engage in one of the apertures 34 of said wheel. Secured to the operating-arm 28 and projecting from one side thereof is a stud 38, reinforced or held rigid by means of a block 39. Extending between the side members 17 of the secondary clock, near the upper end thereof, is a rigid bar 40, secured centrally in and projecting from one side of which is a pindle 41, on which is pivotally mounted the upper end of a locking-bar 42. The lower end of this locking-bar is provided with a locking-pin 43, which is adapted to engage in one or the other of the holes 34 of the wheel 35. Intermediate its ends the locking-bar 42 is provided with a stud 44, reinforced by a block 45, and carries on its outer end a diamond-shaped cam 46, which is positioned to coöperate with the stud 38, carried by the operating-lever 28. The operation of the locking-arm and of the operating-arm will be readily understood from an inspection of the drawings and may be briefly described as follows: When the magnets 18 and 19 are energized, the armature 24 will be attracted by the cores 26, which will cause the outer end of the lever-arm 27 to be drawn downward in opposition to the weight 29 at the opposite end. The lever-arm 27 in its downward movement carries the operating-arm 28 downward, and, as the pin 32 is in engagement with one of the apertures 34 in the wheel 35, said wheel will be revolved. In the downward movement of the operating-arm 28 the stud 38 thereon will engage one side of the cam 46 on the locking-arm 42 and cause said arm to be swung outward to move its pin 43 from engagement with an aperture of the wheel 35. In the further downward movement of the operating-arm 28 the wheel 35 will therefore be rotated through a greater or less arc of a circle, depending upon the length of throw of said operating-arm. The limit of downward movement of said operating-arm may be accurately adjusted by means of a screw 47, passed vertically through and having screw-threaded engagement with the bar 40, as shown by Fig. 1. As said operating-arm reaches the downward limit of movement the stud 38 passes off of the cam 46 and allows the locking-bar 42 to swing inward, so that its pin 43 may again pass into a succeeding aperture 34, which will have been brought into register with said pin by the predetermined movement of the wheel 35, actuated by the operating-arm 28.

As will be clearly seen from an inspection of Figs. 2 and 7, the circuit through the battery and the electromagnets will be closed when in the rotation of the contact-maker 6 one of the contact-pieces 8 comes into engagement with the contact-arms 9 and 10. When this occurs, the electromagnets are energized and the downward movement of the operating-arm 28 follows, as above described. When the contact-piece 8 passes from under the contact-arms 9 and 10, the latter descend upon the insulating material 7, and thus break the circuit, deenergizing the electromagnets and permitting the weight 29 to again raise the outer end of the lever-arm 27. This latter movement will carry the operating-arm 28 upward. At the beginning of this upward movement of the operating-arm its stud 38 will engage the opposite side of the cam 46 from that which it first engaged, due to the fact that the locking-bar has swung inward, as just above described, and in the further upward movement of said operating-arm the latter will be caused to be swung outward by the stud 38 riding over said cam, thereby withdrawing the pin 32 from an aperture in the wheel 35. As the lever-arm 27 reaches its upward limit of movement the stud 38 will pass off of the cam 46, and the said operating-arm will swing inward and its pin 32 again engage in the next succeeding hole 34 of the wheel 35. In order to insure the prompt reengagement of the pin 32 with the wheel 35 after the stud 38 passes off the cam, I provide on the outer side of the operating-arm, near the top thereof, a lever-arm 48, on which is mounted an adjustable weight 49, and the action of this weight will not only cause the immediate return of the operating-arm to its normal position, but will also hold the pin 32 in engagement with one of the holes of the wheel 35 under a yielding resistance, so that there will be no tendency on the part of the pin 32 to slide out of the hole 34 in which it may be inserted in the movement of the operating-arm until the engagement of the stud 38 with the cam 46 causes such action: In the case of the operating-arm 28, which, as will be seen, moves in arcs of circles in directions at right angles to each other, I can better regulate the movement of said arm by means of a weight carried thereby. In the case of the locking-arm 42, however, which has only a single arc of movement, I employ a spring 50 to insure its prompt return to the vertical position after the stud 38 has passed from engagement with the cam 46. The movement of the lever-arm 27 is adjusted so that the pin 32 will always be moved by said arm a distance equal to the distance separating the centers of two of the apertures 34, so that said apertures will always be brought to alinement with the pins 32 and 43. The upward movement of the lever-

arm 27 is regulated by means of an adjusting-screw 51, having screw-threaded engagement with a bracket-arm 52, secured on the frame.

- 5 The shaft 36, which is rotated by the wheel 35, carries a pinion 53, which is in mesh with a gear-wheel 54, fixedly secured on a shaft 55. The outer end of said shaft is squared, as indicated at 56, to provide an arbor for the minute-hand of the secondary clock and may also be provided with a small thumb-nut 57 for turning the hands of the clock, as hereinafter described. Fixedly secured on the shaft 55 is a cannon-pinion 15 58, which is in mesh with a gear 59, carrying a pinion 60, which in turn is in mesh with a gear 61, carrying an arbor 62 for the hour-hand of the clock. The center pinion 54 and cannon-pinion 58 are so firmly secured upon the shaft 55 that it will be impossible for said shaft to rotate independently of these pinions—that is, to slide around therein—and thus I provide against the minute-hand dropping a greater distance than is desired, 25 which very often occurs in large clocks where the cannon-pinion 58 is secured by friction solely upon the shaft 55. In order to enable the hands of a secondary clock to be set, I provide a lever 63, extending behind the operating-arm 28 and locking-arm 62 and pivotally mounted at one end on the under side of a frame member 64, which supports the electromagnets. This lever-arm is controlled by a spring 65.
- 30 35 A wire or other device (not shown) may, if desired, be connected with the outer end of the arm 63 and passed to the front of the clock, by pulling on which or on the outer end of the lever 63 in a direction toward the face of the clock the operating-arm 28 and the locking-arm 42 will be swung forward to throw their respective pins out of engagement with the apertures in the wheel 35, and the hands may then be turned in the ordinary manner or by means of the thumb-nut 57. Usually, however, the hands of all of the secondary clocks are simultaneously moved to set the clocks through the medium of a make-and-break device. (Shown in Fig. 7.) This 45 50 55 60 comprises a spring-arm 66, which is normally out of engagement with a contact-block 67. The arm 66 is connected by a wire 68 with the wire 20, and the contact-block with the wire 21 by a wire 69. By pressing the arm 66 into engagement with the contact-block 67 the circuit through the battery will be closed and the electromagnets energized to operate the lever-arm 27. By releasing the arm 66 the circuit will be broken and the magnets deenergized. By a repetition of this process the wheel 35 can be turned the required distance to set the hands of the secondary clock 56 at the required position.

65 While I have only shown one secondary clock, it will be clearly understood that where

a number of secondary clocks are employed the wiring will in principle be a mere duplication of that shown in Fig. 7.

Referring to Fig. 4, it will be noted that the cam 46, resting against the stud 38, will have a tendency to prevent the pin 32 from coming out of the aperture in the wheel 35, and in Fig. 5 it will be seen that the stud 38, resting against the cam 46, will have a tendency to keep the pin 43 in engagement with the holes of said wheel. Thus each of the arms 28 42 are alternately held in operative position by each other, due to the fact that the stud 38 alternately engages opposite sides of the cam 46. It will of course be understood that the locking-arm 42 is for the purpose of holding the wheel 35 in the position to which it has been turned by the operating-arm 28.

It will be seen that I depend to a large extent on the force of gravity for operating the parts of the secondary clock, such power acting uniformly under all conditions, whereas with springs there is apt to be a difference in action, owing to different degrees of temperature and from other causes well known.

By forming the armature 24 segment-shaped or substantially segment-shaped, as shown, I provide for the requisite length of throw of the lever-arm 27, while maintaining said armature within easy range of the influence of the electromagnets. Were the ordinary flat armature employed, it would have to be suspended at a greater distance from the magnets than is the case with the present armature in order to secure the necessary length of throw of the lever-arm 27, and this would require the expenditure of more battery-power.

Should it be attempted to set the hands of the secondary clock by turning the mechanism from the hands without employing the lever 63, this action would result through the connection of the gear 54 with the pinion 53 in turning the wheel 35. The edge of the hole in which the pin 32 might then be engaged would bear against the inclined top 33 of said pin, and thereby throw the arm 28 outward, so that the stud 38 would not engage the cam 46, and hence the locking-arm 42 would operate through its pin 32 to prevent the wheel 35 from turning further. Thus the hands are locked against movement in this manner or from having their position disturbed.

Having thus fully described my invention, what I claim as new, and desire to secure by Letters Patent, is—

1. In an electric-clock system, in combination with a master-clock having a circuit-breaker operated by the clock mechanism, a secondary clock having electromagnets, a battery, wires connecting up said battery with said magnets through said circuit-breaker, and mechanism, including a verti- 125 130

cally-movable operating-arm and a swinging locking-arm, actuated by said electromagnets and coacting to operate the clockwork of the secondary clock.

5 2. In an electric-clock system, in combination with a master-clock having a circuit-breaker operated by the clock mechanism, a secondary clock having electromagnets, a battery, wires connecting up said battery with said magnets through said circuit-breaker, and mechanism actuated by said electromagnets for operating the clockwork of the secondary clock comprising a vertically-movable operating-arm, and a swinging locking-arm actuated thereby.

15 3. In an electric-clock system, in combination with a master-clock having a circuit-breaker operated by the clock mechanism, a secondary clock having electromagnets, a battery, wires connecting up said battery with said magnets through said circuit-breaker, mechanism, actuated by said electromagnets, for operating the clockwork of the secondary clock, comprising a pair of swinging arms having relative endwise movement, and means for causing said arms to alternately engage and release the mechanism of the secondary clock.

4. In an electric-clock system, in combination with a master-clock having a circuit-breaker operated by the clock mechanism, a secondary clock having electromagnets, a battery, wires connecting up said battery with said magnets through said circuit-breaker, mechanism, actuated by said electromagnets, for operating the clockwork of the secondary clock, comprising a pair of swinging arms having relative endwise movement, and engaging devices carried by said arms for causing said arms to alternately engage and release the mechanism of the secondary clock.

5. In an electric-clock system, in combination with a master-clock having a circuit-breaker operated by the clock mechanism, a secondary clock having electromagnets, a battery, wires connecting up said battery with said magnets through said circuit-breaker, mechanism actuated by said electromagnets for operating the clockwork of the secondary clock comprising a pair of swinging arms, and engaging devices including a cam carried by one of said arms for causing said arms to alternately engage and release the mechanism of said secondary clock.

6. In an electric-clock system, in combination with a master-clock having a circuit-breaker operated by the clock mechanism, a secondary clock having electromagnets, a battery, wires connecting up said battery with said magnets through said circuit-breaker, mechanism, actuated by said electromagnets, for operating the clockwork of the secondary clock, comprising a pair of

swinging arms, and mechanism, comprising a stud carried by one of said arms and a cam carried by the other, for causing said arms to alternately engage and release the mechanism of the secondary clock.

7. In an electric-clock system, in combination with a master-clock having a circuit-breaker operated by the clock mechanism, a secondary clock having electromagnets, a battery, wires connecting up said battery with said magnets through said circuit-breaker, a pivoted lever-arm carrying an armature for said magnets, and means for operating the clockwork of the secondary clock comprising an operating-arm carried by said lever-arm.

8. In an electric-clock system, in combination with a master-clock having a circuit-breaker operated by the clock mechanism, a secondary clock having electromagnets, a battery, wires connecting up said battery with said magnets through said circuit-breaker, a pivoted lever-arm carrying an armature for said magnets, a driving-wheel for said secondary clock provided with a circular series of equidistant recesses, a swinging locking-arm adapted to engage in said recesses, a swinging operating-arm carried by said lever-arm and adapted also to engage in said recesses, and means carried by said arms to cause them to alternately engage, and be released from engagement with, the recesses of said driving-wheel in the movements of said lever-arm.

9. In an electric-clock system, in combination with a master-clock having a circuit-breaker operated by the clock mechanism, a secondary clock having electromagnets, a battery, wires connecting up said battery with said magnets through said circuit-breaker, a driving-wheel for said secondary clock, means actuated by said electromagnets, for operating the secondary clock, comprising a locking and an operating arm adapted to engage said driving-wheel, and means for simultaneously releasing both of said arms for engagement with said driving-wheel to permit the hands of the secondary clock to be set.

10. In an electric-clock system, in combination with a master-clock having a circuit-breaker operated by the clock mechanism, a secondary clock having electromagnets, a battery, wires connecting up said battery with said magnets through said circuit-breaker, a driving-wheel for the secondary clock provided with a circular series of equidistant apertures, a pivoted locking-arm having a pin adapted to engage in said apertures, a lever-arm carrying an armature for said magnets, a swinging operating-arm carried by said lever-arm and having a pin adapted to engage in the apertures of said wheel, and means carried by said operating and locking arms to cause their pins to alternately en-

gage, and be released from engagement with, the apertures of said driving-wheel in the movements of said lever-arm.

11. In an electric-clock system, in combination with a master-clock having a circuit-breaker operated by the clock mechanism, a secondary clock having electromagnets, a battery, wires connecting up said battery with said magnets through said circuit-breaker, a driving-wheel for the secondary clock provided with a circular series of equidistant apertures, a pivoted locking-lever having a pin adapted to engage in said apertures, a lever-arm carrying an armature for said magnets, a swinging operating-arm carried by said lever-arm and having a pin adapted to engage in the apertures of said wheel, means carried by said operating and locking arms to cause their pins to alternately engage, and be released from engagement with, the apertures of said driving-wheel in the movements of said lever-arm.
12. In an electric-clock system, in combination with a master-clock having a circuit-breaker operated by the clock mechanism, a secondary clock having electromagnets, a battery, wires connecting up said battery with said magnets through said circuit-breaker, a pivoted lever-arm carrying an armature for said magnets, a shaft carrying a driving-wheel for the secondary clock, said

wheel having a circular series of equidistant apertures, a pivoted locking-arm having a pin adapted to engage in said apertures, an operating-arm swiveled on said lever-arm and having at its outer end a pin adapted to engage in said apertures, a guide-arm rotatably mounted at one end on said shaft and at its other end pivotally connected to the outer end of said operating-arm, and means carried by said operating and locking arms to cause them to alternately engage, and be released from engagement with, the apertures of said driving-wheel in the movements of said lever-arm.

13. In an electric-clock system, in combination with a master-clock, a secondary clock having electromagnets provided with cores having circularly-recessed ends, a substantially segment-shaped armature mounted for rocking movement in juxtaposition to said cores, and means, comprising a lever-arm secured to said armature, and a vertically-movable operating-arm pivoted to said lever-arm for actuating the mechanism of the secondary clock.

In testimony whereof I have hereunto set my hand in presence of two subscribing witnesses.

HENRY IVERSEN.
